G. NEAL, OF SPRINGFIELD, MASSACHUSETTS

APPARATUS FOR CLEANING PAPER STOCK

Application filed March 11, 1930. Serial No. 434,897.

This invention relates to a method and apparatus for cleaning pulp. It is useful primarily in cleaning pulp just before the latter is fed onto the wire of a Fourdrinier paper making machine. In such machines it is common to provide "sand traps" for pulp cleaning purposes. My invention provides an improved pulp cleaner to use in place of the common "sand traps".

10 The common "sand trap" is a shallow trough over which the pulp (suspended in water) flows and the impurities like sand settle to the bottom. To aid this settling, riffle bars extend across the trough at short 15 intervals to stop the current near the floor of the trough. Such "sand traps" offer various objections. They need to be cleaned frequently and this causes trouble and expense. The attempt to trap the sand and impurities 20 is partially defeated by the nature of the stagnant pools between the riffle bars, and the pulp is not always cleaned as well as it can be.

According to my invention I provide a 25 movable floor in a cleaning trough upon which the impurities are caused to settle. This floor can be moved out of the trough, cleaned, and put back in place without necessarily interrupting the flow of pulp through 30 the trough or stopping the continued functioning of the cleaner.

The preferred means for this purpose is a 35 moving conveyer belt. The surface of the belt is arranged to serve the bottom of the trough as its settling floor. The belt is preferably moved oppositely to the flow of pulp. As the sediment gradually settles on the moving floor it is carried out of the trough to a 40 station where it can be washed from the movable floor and the clean floor returned to the bottom of the trough, all in one continuous movement. The large advantage in this means is, I believe, in the nature of the cleaning method. This method permits the desired sedimentation without any accumulation 45 of the sediment to build up a stagnant condition in the pulp cleaner. The method also permits the sediment to be removed from the pulp cleaner in such a manner as to avoid 50 its being stirred up again after it has been

once deposited on the cleaner floor. Of course the continuity of the cleaning operation is important and desirable, but I wish to point out that the manner in which the pulp cleaner is kept in condition for its primary 55 function is more important.

Another important feature of my invention is in providing a special form of pulp cleaning belt as an element in the improved cleaner. The conveyer belt, according to this feature, is preferably made of felt. According to another feature the felt belt has a long nap. This belt can be made endless and of considerable thickness like felt belts now used at other places in paper machines, but 60 the nap is made preferably (but not necessarily) longer. I prefer to use such a belt for the movable floor of the pulp cleaner. The nap will act to gather the sediment from the pulp and hold it throughout the slow 65 travel of the belt from one end of the trough to the other. I feel that such a nap on the belt will gather sediment from the pulp which would otherwise not settle but remain as free dirt in the flow of pulp to the machine. 70

There are other features of the invention which will be brought out in connection with the accompanying drawings, detailed description, and annexed claims.

In the drawings—

Fig. 1 is a longitudinal section of the new pulp cleaner in the preferred form and in sufficient detail to make the operation clear;

Fig. 1—A is a modification of the location of the wringer rolls in Fig. 1;

Fig. 2 is a plan view of Fig. 1; and

Fig. 3 is an end view.

To save drawing space in Figs. 1 and 2 a part of the middle section of the cleaner is broken away and that part merely indicated 90 by dotted lines.

The cleaning trough 1 as a container may be substantially like the trough of the ordinary "sand trap". Pulp inlet 2 at one end and outlet 3 at the opposite end are of the usual arrangement.

The endless belt 4 is guided on suitable pulleys 5 for a portion to lie along the bottom of the trough from one end to the other and serve as the floor of the trough 1 so far as any 100

deposition of sediment is concerned. As the belt is led out of the trough at the feed end, it passes between two wringer rolls 6 and 7, one of which may be the driving pulley for 5 the belt. The belt then travels over its pulleys to a cleaning station where a whipper device 8 beats the sediment loose and spray devices 9 shower water on and through the felt belt to carry all sediment to the under- 10 lying collecting hopper 10. The sides of this hopper are washed from spray pipes 11. The collecting surface of the belt is of course fac- 15 ing downwardly in its travel over the collecting hopper. So sediment falls off, is knocked off, and is washed off, to clean the belt surface before it returns to the trough. Just before the cleaned surface reenters the trough I provide a device 12 comprising a roll with a combing surface as indicated to 20 pick up and loosen the nap. The belt surface thus starts its travel along the bottom of the trough in clean condition and with its nap all "furred up" to collect all possible sediment and dirt from the bottom zone of the 25 pulp flow through the trough.

In the operation of cleaning the pulp by my apparatus a substantial amount of fiber may be carried out of the trough by the belt. That is to say, there may be a small percent- 30 age with each turn of the belt and in the long run the amount may become substantial. For this reason I provide an auxiliary cleaner 13 into which the collecting hopper 10 guides all the dirt and wild fiber. This cleaner may 35 be of a usual type such as are provided with an agitated screen or series of screens to separate the coarse particles from the fine pulp. A sufficient separation is obtained so that the fiber can be reclaimed by pumping it back 40 to the inlet end of the pulp cleaning device above to again pass into the trough. I have not shown the detail of the auxiliary cleaner as these structures are known. Only the dirt outlet 14 and the reclaimed pulp fiber outlet 45 15 from this cleaner need be considered in understanding my arrangement. The latter outlet is shown leading to a pump 16 and to the inlet supply 17 for the primary cleaner.

In the trough 1, I prefer to provide cross 50 slats 18. These are arranged somewhat like the riffle bars in the ordinary "sand trap" except that they do not rest on the floor of the trough. In my trough they are preferably spaced far enough above the floor to 55 avoid scraping the belt and yet not far enough to provide for any substantial flow of pulp under their bottom edges. I also preferably incline them against the pulp flow instead of oppositely as in the case of 60 riffle bars generally. These slats 18 may be mounted for ready adjustment both with respect to their inclination and their distance above the trough floor. Their object is to 65 control the pulp flow so as to help bring about the desired deposit of sediment on the

floor of the trough. By my arrangement, however, perfectly dead or stagnant corners and pockets are avoided in the flow and yet the possible circulation is slow enough to help the dirt to settle.

The travel of my belt along the bottom of the trough may be so slow as to avoid any appreciable effect in the movement of the pulp. The movement of the latter from the inlet to the outlet of the trough may take 75 place in substantially the same way as if the floor of the trough were stationary. The deposit of the sand and sediment can take place in the same way as if the floor were stationary, except that by effecting the removal and 80 cleansing of the floor the sedimentation is carried on better because there is no accumulation of dirt to gradually saturate the region where sedimentation should take place.

In my above description of the operation I have confined the plan to an operation somewhat parallel to the "sand trap" operation of simple deposition on the floor of the trough. The invention is good for that purpose, but other advantageous operations are feasible and sometimes of advantage. By moving the belt faster I can bring the nap of the felt into more effective operation for combing the bottom strata of the pulp flow. 95 This would be of advantage in some cases. By ready adjustment of the belt speed I can accommodate the cleaner to the kind of pulp (meaning also the amount and/or kind of foreign matter to be removed) being cleaned, 100 or to various modes of operation on the same pulp to get the best results. Where the belt has its speed increased the amount of pulp taken out with the dirt tends to increase, but with my auxiliary cleaner arranged to automatically return this pulp to the trough, that 105 difficulty is nicely overcome.

It may be desirable in some cases to provide a trough to take away the water squeezed out of the belt by the wringer rolls instead of returning it to the trough. This water may be 110 too dirty to return, in which case it can be diverted to the collecting hopper. I have shown this slight modification at Fig. 1—A.

Many other modifications and variations in the different details of my invention, both in structure and mode of operation, may be made without departing from its characteristics now to be pointed out in the following 115 claims.

What I claim is:

1. A cleaning apparatus for pulp and the like comprising a container provided with spaced inlet and outlet between which a flow 125 can be maintained, a movable sediment collecting floor having excess surface for the container, and means to maintain said floor between the inlet and outlet upon moving it toward one end of the container and then out 130

of the flow and toward one end of the container and into the flow.

2. A cleaning apparatus for pulp and the like comprising a settling trough through which pulp may flow, a flexible member having portions arranged to serve as the settling floor for the trough, and means to change said portions without interrupting the flow.

3. A cleaning apparatus for pulp and the like comprising a settling trough through which the pulp may have a continuous flow, an endless belt and guide means to hold successive portions of the belt at the bottom of the trough to serve as a collecting floor whereby the sediment may be gently removed from the trough before it accumulates to an objectionable degree.

4. A cleaning apparatus for pulp and the like comprising a settling trough through which the pulp may have a continuous flow, an endless belt, guide means and driving means to pass the belt into the trough and from one end to the other to serve as a collecting floor and then out of the trough whereby the floor may be cleaned without interrupting the pulp flow through the trough.

5. A cleaning apparatus for paper pulp comprising a continuous flow settling trough, a movable endless belt to serve as the settling floor of the trough, driving means for the belt and also guiding means therefor arranged to carry one belt flight from end to end of the trough and the other flight to return it outside the trough, and means to clean the belt arranged adjacent the second flight.

6. A cleaning apparatus for paper pulp comprising a continuous flow settling trough, an endless belt of felt with a nap to assist the cleaning operation, guide and driving means for said belt arranged to carry it in at the outlet of the trough and along the bottom to serve as the settling floor for the trough and out of the trough at its inlet end, and means to clean the belt in its path back to the inlet end of the trough.

7. A cleaning apparatus for paper pulp comprising a continuous flow settling trough, an endless belt of felt with a nap to assist the cleaning operation, guide and driving means for said belt arranged to carry it in at the outlet of the trough and along the bottom to serve as the settling floor for the trough and out of the trough at its inlet end, means to clean the belt in its path back to the outlet end of the trough, and means to raise the nap on the belt after it is cleaned.

8. A cleaning apparatus for paper pulp comprising a settling trough like a "sand trap", a felt floor for the trough, and means to hold said floor in position while permitting successive portions of it to be removed from the trough for cleaning and other portions to be inserted to maintain the floor area without interrupting the flow of pulp along the floor.

9. A constant flow pulp cleaning apparatus arranged to deliver cleaned pulp to a constantly running paper making machine, said apparatus comprising a settling trough with means to regulate the pulp flow from one end to the other, an endless belt and guide means to hold successive portions of the belt to serve at all times as the floor of the trough, means to move said belt oppositely to the flow of pulp through the trough and carry successive portions out of the trough for cleaning, and means to clean the belt.

10. A constant flow pulp cleaning apparatus arranged to deliver cleaned pulp to a constantly running paper making machine, said apparatus comprising a settling trough with means to regulate the pulp flow from one end to the other, an endless belt and guide means to hold successive portions of the belt to serve at all times as the floor of the trough, means to move said belt oppositely to the flow of pulp through the trough and carry successive portions out of the trough for cleaning, means to clean the belt, and means to return pulp fibers taken from the trough by the belt.

11. In a cleaning apparatus an endless felt belt, a cleaning chamber, means to drive the belt through the chamber to collect its dirt, and means to renovate the belt outside the chamber, all arranged for continuous operation.

12. A long flow box located in the feed apparatus for a paper making machine, means to control the flow of pulp through said box to permit impurities to settle, an endless belt having a surface arranged to receive the impurities at the bottom of the box, and deliver them outside the box without interrupting the operation of the feed apparatus.

13. In combination for the purpose described, a flow box, a fabric belt to serve as the floor of the box, and means to take successive portions of the belt outside the box, clean them and return them to the box without interrupting the flow, said means including wringer rolls, a shower device, a beater, and a nap lifter.

14. A settling apparatus for cleaning paper stock, having a passage for slow flow of the material, an endless belt with a portion serving as the floor of said passage, cleaning means for the belt, driving means for the belt and cleaning means, all arranged to maintain a settling floor for the passage without storage of sediment thereon.

15. The combination in a paper stock cleaner of a settling container arranged for constant flow from end to end, a belt and guide means, a portion of said belt serving as the floor of the container and the rest of the belt looped outside and underneath the container, and means to clean the belt in its passage along said loop.

16. The combination in a paper stock

cleaner of a settling container arranged for constant flow from end to end, a felt belt and guide means, a portion of said belt serving as the floor of the container and the rest of the belt looped outside and underneath the container, wringer rolls for said belt outside the container, a shower device and dirt loosening device adjacent the belt underneath the container, and a nap renovator device adjacent the belt outside the container.

17. The method of taking dirt like sand, etc. from paper stock as it flows to the paper making machine which consists in running the stock over a portion of an endless belt long enough to permit separation of the dirt by sedimentation on the belt, guiding said belt out of the stock to clean the belt and returning it in cleaned condition without interrupting the flow of stock to the machine.

29 In testimony whereof I have affixed my signature.
